UNITED STATES PATENT OFFICE.

ANTON FETTING WALTZ, OF NEW YORK, N. Y.

TOILET OUTFIT.

1,267,941.

Specification of Letters Patent. Patented May 28, 1918.

Application filed September 19, 1917. Serial No. 192,082.

To all whom it may concern:

Be it known that I, ANTON FETTING WALTZ, a citizen of the United States, and a resident of the city of New York, borough 5 of Manhattan, in the county and State of New York, have invented a new and Improved Toilet Outfit, of which the following is a full, clear, and exact description.

The object of the invention is to provide 10 a new and improved toilet outfit including a pair of military brushes arranged to permit their use for brushing the hair in the usual manner and to form a convenient housing for toilet accessories or toilet articles 15 such as a toothbrush, powder box, safety razor and the like.

In order to accomplish the desired result, use is made of a brush having a hollow back provided in its side wall with an opening, a 20 drawer adapted to fit into the said hollow back and adapted to be removed or inserted through the said opening, the latter extending from one end of the back to approximately the middle of the sides of the side wall, 25 the said drawer completely closing the said opening and the drawer having its sides provided with shoulders abutting against the ends of the side wall of the brush back. Use is also made of a drawer having in its 30 bottom a compartment for the reception of a mirror, the compartment being open at the rear to hold the mirror against movement at the time the drawer is inserted in the brush back.

35 A practical embodiment of the invention is represented in the accompanying drawings forming a part of this specification, in which similar characters of reference indicate corresponding parts in all the views.

40 Figure 1 is a side elevation of one of the brushes of a pair of military brushes;

Fig. 2 is a sectional plan view of the same on the line 2-2 of Fig. 1;

45 Fig. 3 is a longitudinal sectional elevation of the other brush of a pair of military brushes; and

Fig. 4 is a sectional plan view of the same on the line 4-4 of Fig. 3.

The toilet outfit includes a pair of military brushes 10 and 11, each practically alike in construction, each having a back 12 made hollow and provided at its bottom 13 with the usual bristles 14. The hollow back 12 is provided in its side wall 15 with an opening 16 which extends from one end of the back 12 to approximately the middle thereof

to permit of conveniently inserting or removing a drawer 20. The drawer 20 for the brush 10 is provided with a bottom 21 and a side wall or rim 22 which terminates a 60 distance from the rear end of the drawer, as plainly indicated in Figs. 1 and 2. The rim 22 is provided exteriorly and at its middle with shoulders 23 abutting against the ends of the side wall 15 of the brush 65 back 12, as plainly indicated in Fig. 2. The drawer when inserted in the hollow back 12 completely closes the opening 16 of the side wall 15, and the drawer when in this position is adapted to be fastened therein 70 by a suitable latch 24, preferably pivoted on the bottom 13 of the back 12, and adapted to be swung upward into the path of the end of the rim 22, as will be readily understood by reference to Fig. 1. The bottom 21 of the 75 drawer 20 for the military brush 10 is provided on its upper surface with retaining devices 30 and 31, preferably in the form of loops, of which the retaining device 30 is adapted to hold a folding toothbrush 32 80 and the retaining device 31 is adapted to hold a dental powder box 33. It will be noticed that when the drawer 20 for the brush 10 is in position therein the toilet articles mentioned are completely incased, 85 and when the drawer is removed from the back 12 then the toilet articles 32, 33 can be removed endwise through the opening at the rear end of the drawer 20. In a like manner the toilet articles can be reengaged 90 with the retaining devices 30 and 31 through the rear open end of the drawer 20.

The drawer 20 for the military brush 11 is similar to the one for the military brush 10 with the exception that its bottom 40 95 is provided with a compartment 41 open at the rear end 42 for the insertion or removal of a mirror 43, the mirror being provided with a suitable pivoted handle in the form of a ring 44 located at the end of the mirror 100 adjacent the open end 42 so that the ring can be conveniently taken hold of by the user. The upper surface of the bottom 40 is provided with retaining devices 50, 51 for holding a safety razor 52, the handle 53 105 of which is held in retaining devices 54 and 55 likewise arranged on the upper surface of the bottom 40. Another retaining device 56 is arranged on the upper surface of the bottom 40 for holding a package 57 110 containing extra razor blades 58. The upper surface of the bottom 40 is preferably

lined with felt 60 or similar material to prevent undue scratching of the safety razor 52 or its handle 53.

It is understood that I do not limit myself to the particular articles removably mounted in the various retaining devices 30, 31, 50, 51, 54, 55 and 56, as other articles besides those shown and described may be accommodated in the drawers 20 of the 10 two brushes 10 and 11. The toilet outfit shown and described is very serviceable for military men, travelers and other persons.

It is expressly understood that the rims 22 of the drawers 20 form continuations of 15 the rims or walls 15 of the backs of the brushes 10 and 11 so that the backs can be readily grasped and firmly held in the hands of the user when utilizing the brushes for brushing hair.

20 It will also be noticed that the drawers can be readily unlocked or removed from the brush backs to permit removal and convenient use of articles carried thereby. By reference to the drawings it will be noticed 25 that the terminals of the rims 22 fit against the inner surfaces of the rims 15 of the brush backs to hold the drawers 20 against accidental lateral movement.

Having thus described my invention, I 30 claim as new and desire to secure by Letters Patent:—

1. In a toilet outfit, a brush having a hollow back provided in its side wall with an opening, a drawer adapted to fit into 35 the said hollow back and adapted to be inserted or removed by way of the said opening, the latter extending from one end of the back to approximately the middle of the sides of the side wall, the said drawer completely closing the said opening, the 40 drawer having its sides provided at a distance from their ends with exterior shoulders abutting against the ends of the side wall of the back.

45 2. In a toilet outfit, a brush having a hollow back provided in its side wall with an opening, a drawer adapted to fit into the said hollow back and adapted to be inserted or removed by way of the said opening, the latter extending from one end of the back to approximately the middle of the sides of the side wall, the said drawer completely closing the said opening, the drawer having its bottom extending beyond its 50 sides and the upper surface of the bottom of the drawer being provided with retaining devices and toilet articles held in position in the said retaining devices and removable therefrom by the open rear end 55 of the drawer when the latter is withdrawn from the hollow back.

3. In a toilet outfit, a brush having a hollow back provided in its side wall with an opening extending from one end of the back to approximately the middle of the sides of the said side wall, a drawer fitting into the said hollow back and adapted to be inserted or removed through the said opening, the drawer having a bottom and a side wall terminating short of the end of the bottom and having exterior shoulders engaging the ends of the wall of the back, and retaining means held on the upper face of the said drawer bottom for holding toilet articles. 65 70 75

4. In a toilet outfit, a brush having a hollow back provided in its side wall with an opening extending from one end of the back to approximately the middle of the sides of the said side wall, a drawer fitting into the 80 said hollow back and adapted to be inserted or removed through the said opening, the drawer having a bottom and a side wall terminating short of the end of the bottom, the side wall of the drawer being provided 85 at a distance from the end thereof with exterior shoulders adapted to abut against the ends of the side wall of the back, retaining means held on the upper face of the said drawer bottom, and toilet articles held in 90 position in the said drawer by the said retaining devices, the said toilet articles being adapted to be engaged with the said retaining devices or removed therefrom through the said open rear end at the time 95 the drawer is removed from the hollow back.

5. In a toilet outfit, a military brush having a hollow back open at one end, and a drawer slidably fitting into the said hollow back and closing the open end, the drawer having in its bottom a compartment for the reception of a mirror, the compartment being open at the rear to hold the mirror against movement at the time the drawer 100 is inserted in the brush back. 105

6. In a toilet outfit, a military brush having a hollow back open at one end and a drawer slidably fitting into the said hollow back and closing the said open end, the drawer having in its bottom a compartment for the reception of a mirror, the compartment being open at the rear, the side wall of the drawer terminating near the rear end of the drawer, and retaining devices on the upper surfaces of the drawer bottom and adapted to hold toilet articles adapted to be inserted or removed through the open rear end of the drawer at the time the latter is withdrawn from the brush back. 110 115

ANTON FETTING WALTZ.
